(57) **CLAIM**

The ornamental design for a chair, as shown and described.

DESCRIPTION

FIG. 1 is a front perspective view of a chair showing my new design;

FIG. 2 is a right side view thereof, with the left side view being a mirror image;

FIG. 3 is a back view thereof;

FIG. 4 is a front view thereof;

FIG. 5 is a top view thereof;

FIG. 6 is a bottom view thereof;

FIG. 7 is a front perspective view of an alternative embodiment of a chair showing my new design;

FIG. 8 is a right side view thereof, with the left side view being a mirror image;

FIG. 9 is a back view thereof;

FIG. 10 is a front view thereof;

FIG. 11 is a top view thereof; and,

FIG. 12 is a bottom view thereof.

In the drawings, the broken lines represent portions of the chair which form no part of the claimed design.
